PEDESTAL SUPPORTED ROTARY TABLE TOP
CENTER SECTION

Charles A. Bartschy, Kelso, Wash.

Application March 25, 1949, Serial No. 83,401

2 Claims. (Cl. 311—33)

1

The invention relates to an improved table of the type having a rotatable or rotary center section in its top, the primary object of the invention being to provide a more practical and serviceable table of this character which is especially suitable for use in restaurants and other commercial establishments, such as manufacturing or assembling plants.

Other objects and advantages of the invention will appear in further detail as the specification proceeds.

In order to facilitate ready comprehension of this invention and a proper appreciation of the salient features thereof, a specific embodiment of the invention is illustrated in the accompanying drawings forming part hereof, and in which:

Figure 1 is a perspective view;

Figure 2 is a horizontal section taken on line 2—2 in Figure 1;

Figure 3 is a fragmentary transverse vertical section taken on line 3—3 in Figure 2.

In the views, the same reference numerals indicate the same or like parts.

Referring in detail to the drawings, the illustrated table, generally designated 4, comprises a group of feet 5 secured together in a cruciform design to the lower end 6 of a vertical cylindrical pedestal 7, about whose upper part are secured a group of circumferentially spaced, radially outwardly and upwardly-extending supporting arms generally indicated at 8, 9. The supporting arms 8 each consist of a radially-extending horizontal strip of metal bent downwardly to form a depending lug 10 at the inner end thereof, secured by a pair of screws 11 to the pedestal 7, the outer part of the arm 9 being curved upwardly at 12 and formed at its outer end with a radially outwardly extending attachment lug 13, secured by screws 14 to the underside of a stationary annular table top section 15. The section 15 is enclosed by a covering including a channel 16 of plastic or metal engaging over its outer peripheral edge. A diagonal brace 18 of metal strip has its lower and radially inward end secured, as indicated at 17, as by welding or brazing, to the inward end of the supporting arm portion 9 and has its radially outward or upper end similarly secured, as indicated at 19, to the upper and outward end of the arm portion 12. In addition, a horizontal brace 20, also formed of metal strip, is bent downwardly at the inner end thereof to form an attachment lug 21 which is secured by a pair of screws 22 to the upper part of the pedestal 7 and has its outer end welded or brazed, as indicated at 23, to an intermediate portion of the diagonal brace 18. The result is

2

that each of the supporting arms 8 is a lightweight but rigid and firm supporting structure for the ring shaped table top section 15. The inclusion of several such supporting arms secured to the pedestal 7 and to the underside of the stationary table top section 15 at equidistantly spaced points adequately supports the same and provides at the same time free access to the underside of the table top and the pedestal for cleaning or other purposes.

The annular stationary section 15 has a central circular opening 24, and the inner peripheral edge of the section 15 is provided with a reinforcing channel 25 to present a perfectly circular, smooth, and reinforced edge. Cooperating with the section 15 to complete the table top is a circular center table top section 6 which occupies the opening 24, and is provided on its peripheral edge with a finishing and reinforcing channel 27. The rotary section 26 is supported in flush relation with the top of the stationary section 15. To the center of the underside of the rotary section 26 is secured a metal disc 28 by means of a group of screws 29 and the disc 28 has therein an arcuate finger hole or slot 30, into which the fingers can be thrust to facilitate handling the rotary section 26 from below when required. To the center of the underside of the disc 28 is brazed or welded a vertical axis nut 31.

The upper end 32 of the pedestal 7 is formed with an upwardly opening cylindrical recess 33 in which is fitted an upwardly opening metal cylinder 34 terminating flush with the upper end of the pedestal and having a closed bottom 35. Within the hollow cylinder 34 and resting upon the bottom 35 thereof is a ball thrust bracing 38 which includes a lower ball race 36 which is wedged in the cylinder by means of a shim 37, and has an upper annular ball race 41. Within the upper end of the hollow cylinder 34 is force-fitted a ball bearing 39 having an outer race 40 and an annular inner race 41. Into the above mentioned nut 31 is screwed the upper threaded end of a reduced portion 42 of a spindle 43 which is axially positioned in the cylinder 34. The reduced portion 42 extends through the opening of the annular inner race 41 and defines an upper shoulder 44 which supportably engages the underside of the inner race 41. At its lower end the spindle 43 is provided with a reduced portion 45 which extends through the opening of the upper race 47 and defines a lower shoulder 46 which rests upon the upper ball race 47 of the thrust bearing 38, the upper race 47 being arranged so that the thrust bearing 38 supports 55 the combined weight of the spindle 43 and the

rotary table top section 26, while the upper ball bearing 38 holds the rotary section 26 centered in the table top opening 24 and eliminates transverse strains and displacements thereof relative to the pedestal 7 and the stationary table top section 15 and allows free rotation of the rotary section 26 within the opening 24 in the stationary section 15. The annular stationary section 15 may be covered with coating material 48, and similarly the rotary section 26 may be provided with surfacing material 49, the two sections being flush in such a manner that articles can be freely slid thereon across the table top in any direction.

The arrangement is such that if the table is used in a restaurant, for example, various containers of condiments, sauces, and supply dishes placed upon the rotary section 26 will be readily accessible to a group of persons seated around the table, since the rotary section can be easily rotated to bring any of the various containers or dishes within reach of any of the group. While one of the group is being served from a main dish, others of the group can momentarily use the containers or dishes from the rotary section 26, and after replacing the containers or dishes thereon the rotary section 26 can be rotated in step-by-step fashion to make the container available in succession to the various members of the group. The table can also be used for assembling apparatus by having a group of assemblers around the table with a supply of parts on the rotary section 26, so that the rotary section 26 can be rotated step-by-step to confront each successive assembler in turn with the proper parts.

Manifestly, variations may be resorted to and parts and features may be modified or used without others within the scope of the appended claims.

Having now fully described my invention, I claim:

1. In a table, a pedestal formed in its upper end with a recess, a hollow cylinder fitting said recess, said cylinder having an open upper end and a closed bottom, a lower ball thrust bearing supported on the bottom of said cylinder having an annular upper race, a spindle positioned axially in said cylinder having a reduced lower end portion extending downwardly through the opening of said annular upper race, said reduced lower end portion defining a lower shoulder on said spindle supportably resting upon said upper race, an upper annular bearing fixed in the upper end of said cylinder, said spindle having a reduced

upper end portion extending upwardly through the opening in said annular bearing, said reduced upper end portion defining an upper shoulder on said spindle bearing against the underside of said annular bearing, a circular rotary table top section fixed centrally upon said spindle above said upper annular bearing, and an annular stationary table top section fixedly mounted on said pedestal and surrounding said rotary table top section.

2. In a table, a pedestal formed in its upper end with a recess, a hollow cylinder fitting said recess, said cylinder having an open upper end and a closed bottom, a lower ball thrust bearing supported on the bottom of said cylinder having an annular upper race, a spindle positioned axially in said cylinder having a reduced lower end portion extending downwardly through the opening of said annular upper race, said reduced lower end portion defining a lower shoulder on said spindle supportably resting upon said upper race, an upper annular bearing fixed in the upper end of said cylinder, said spindle having a reduced upper end portion extending upwardly through the opening in said annular bearing, said reduced upper end portion defining an upper shoulder on said spindle bearing against the underside of said annular bearing, a circular rotary table top section fixed centrally upon said spindle above said upper annular bearing, and an annular stationary table top section fixedly mounted on said pedestal and surrounding said rotary table top section, said reduced upper end portion being threaded and said rotary table top section having a nut secured to its underside into which the threaded reduced upper end portion of the spindle is threaded.

CHARLES A. BARTSCHY.
